PROCESS OF MAKING PATENT-LEATHER SHOES.

1,115,680.

Specification of Letters Patent.

Patented Nov. 3, 1914.

Application filed July 11, 1914. Serial No. 850,288.

To all whom it may concern:

Be it known that I, JOHN A. KELLY, a citizen of the United States, residing at Philadelphia, county of Philadelphia, and State of Pennsylvania, have invented a certain new and useful Process of Making Patent-Leather Shoes, of which the following is a specification.

This invention is a process of making footwear the material of which is composed usually of leather provided with an enamel coating presenting a normally finished surface.

It is well known to those skilled in the art that one of the serious problems connected with enamel coated boots and shoes is to preserve the coating free from cracks and blemishes, but this is especially so in the process of lasting and otherwise manipulating the article during the manufacture thereof. The enamel coating is of such peculiar character that it will crack in comparatively moderate temperatures, as during cold weather, and even during the manufacture of the shoe when it is carried from one room to another or from one floor to another in the factory.

In the manufacture of footwear from enamel coated material it is usual to immerse the toe portion of the upper prior to lasting in water for the purpose of softening the material so as to facilitate lasting the upper; sometimes the same result is attained by steaming the upper. When the upper is lasted the toe portion thereof is usually "wiped in" by a machine known in the trade as a wiper, but owing to the strain imposed on the toe portion of the upper during such lasting operation the enamel coating at the toe portion becomes cracked, it being estimated that about 90% of all patent leather shoes are defaced during manufacture. The cracking of the coating is pronouncedly observable subsequent to lasting the upper, and it is due, first, to the strain or pull upon the upper, to the drying out of the material previously moistened to facilitate lasting, and to a marked extent to the contact of the air with the enamel coating, such air contact with the moistened enamel resulting in fine blemishes referred to as "air cracks". At times it is observable that an enamel coated shoe will leave the lasting machine apparently in good condition, but after several days following the

lasting operation the coating, having been exposed to the air, will pronouncedly crack and blemish, this being noticeably the case when the shoe is under strain or before removing it from the last. As previously noted herein, the enamel will crack when the shoe is subject to temperature changes or to air contact during the manufacture thereof, and it is customary to place the shoes in warm rooms in order to minimize the serious fault of cracking in the enamel. It is apparent that enamel shoes with cracked toe portions are not merchantable articles, hence it becomes necessary to refinish the shoe at the factory and before shipping it to the dealers. Such refinishing is done as follows:—A workman scours off the enamel at the cracked toe portion of the upper so as to smooth down the surface of the underlying leather. Then an enamel filler is applied to the scoured part of the shoe, and as it is not possible to apply the filler by a brush it is the usual practice for the workman to wrap material around his fingers, saturate such material with the liquid filler, and to rub such liquid filler thoroughly upon the scoured leather toe portion. It is apparent that this requires skilled labor, and involves time and expense, experience having shown that expert workmen are not able to refinish more than fifty pairs of shoes per day. Usually, two or more coatings of the liquid filler are required, and it must be applied uniformly and with exercise of good judgment, for the reason that if the coating should be too thin the enamel will fade out, but if it is too thick the enamel will be sticky, particularly in damp weather, as a result of which there will adhere to the refinished coating the paper or other material in which the article is incased. All this increases the cost for the reason that the enamel material and the flow material are expensive, and the labor cost is no inconsiderable item, for the reason that skilled labor must be used, and at times such labor is not available, thus seriously hampering the shipment of goods at a time when a demand exists therefor. It should be stated that after applying the filler material in refinishing the scoured part of the toe, it is customary to apply a flow material, such as alcohol which is rubbed by hand over the enamel so as to smooth and brighten up the surface.

From what has been said as to the disadvantages inherent in the manufacture of enamel coated footwear it is readily understood and appreciated that the manufacture 5 is more or less costly and the product is not free from defects.

The purpose of my invention is to overcome the foregoing and other objections by an improvement in the art which entirely 10 overcomes all tendency of the enamel coating to crack at the toe portion of the upper during lasting thereof or subsequently to such lasting, so as to entirely avoid and dispense with the operation of refinishing 15 the enamel material, and to accomplish this at a substantial saving in the labor and material required in such refinishing operation, and to produce a superior finished article.

Broadly stated, my improvement in the art 20 of making enamel coated footwear consists in the use of a protective covering for the toe portion of the upper, which covering remains in position during the operation of lasting the upper and preferably during the subsequent 25 manipulation of the article until it is finally completed and the last removed, such protective covering operating in a twofold capacity of taking the strain off the enamel coating at the toe of the upper when the latter is drawn tightly around the last and 30 as a means of keeping the coating from contact with the air during the period of setting the upper to the required form or shape, whereby cracking of the enamel coating 35 is wholly precluded.

The preferred mode of procedure is as follows:—Prior to placing the upper on a last, a suitably shaped piece of material, such as rubber fabric, is placed upon the 40 toe portion of the upper and in contact with the enamel coating thereof, such material being united to the upper. Assuming that rubber fabric is used, a hot iron or other tool is run over the fabric, the effect 45 of which is twofold; first, the fabric adheres to the enamel coating and, second, the latter is softened to an appreciable extent so as to render it pliable and suitable for lasting without being compelled to resort to 50 the usual expedient either of saturating the upper by immersing it in water or by steaming it. The upper is now lasted in the usual way and by the usual means, but at this time the utility of the fabric serving as 55 the protective covering becomes the more apparent for the reason that it not only takes the strain off the enamel coating but it prevents the "wipers" of the lasting machine from adhering to the enameled material and it overcomes direct contact of the sharp wipers with such material, thus precluding cutting of the enamel which occasionally happens. The fabric is thus lasted 60 with the upper and it remains applied there-

to during the subsequent manipulation of 65 the article or until the last is removed. The fabric thus protects the enamel coating during the period of drying the upper or of allowing the enamel to set, as a result of 70 which the enamel is not cracked either during the lasting operation or by contact with the air during the setting of the enamel or by atmospheric changes. When the article 75 is completed and the last removed, the next step is to remove the fabric covering, and this is done by cutting it free from the sole, after which the upper at the toe is cleaned by applying a solvent such as benzin to remove the rubber material of the fabric, thus 80 wholly cleaning the upper by eliminating the rubber adhesive from the enamel coating so that the wrapping paper will not adhere thereto. Not only will the enamel not crack during the operation of lasting the upper, nor when the upper is exposed to the air, but 85 this objectionable condition will not arise after the shoe is completed and the protective fabric is removed, for the reason that the upper will dry and the enamel will set before the cover is taken off, as a result of 90 which cracking cannot take place for the reason that the enamel is in a permanently set condition.

My procedure secures a superior article 95 at less cost of manufacture for the reason that it is not necessary to refinish the toe portion of the upper to eliminate the blemish due to cracking of the enamel.

In the drawings, Figure 1 is a plan view of a portion of an upper prior to lasting, 100 the toe portion of said upper being flattened out and the fabric applied thereto. Fig. 2 is a longitudinal section through the parts composing the upper prior to lasting, the plane of the section being indicated by the 105 dotted line 2—2 of Fig. 1, and said view showing the upper, the lining therefor, an extra layer at the toe portion to cover the upper proper and the rubber coated fabric applied to the enamel coated surface of a 110 part of the upper. Fig. 3 is a perspective view of the lasted upper and with the protecting fabric retained on the toe portion of said upper and lasted therewith. Fig. 4 is a perspective view illustrating the toe 115 portion of a completed shoe but with the fabric applied thereto. Fig. 5 is a longitudinal section through the shoe of Fig. 4 with the last removed but with the protective fabric still applied to the toe portion of 120 the upper, it being understood that when the shoe is completed said protective fabric is cut off and the enamel coated surface of the shoe is cleaned in a suitable way.

The upper A is made in the usual way, a 125 substantial part of said upper being composed of enamel coated leather or other material. Prior to lasting the upper, a protec-

tive fabric B is applied to the enamel coated material of said upper or to a part only of said material, preferably at the toe portion of the upper. This fabric is cut to conform 5 to the part of the upper upon which said fabric is to be applied. Preferably, the fabric B is a rubber fabric or a fabric backed by rubber, and it is united under heat and pressure to the enamel coating of the upper 10 at the toe portion thereof. Prior to lasting the upper the toe portion is spread out or flattened, and the rubber surface of fabric layer B is laid upon the enamel coating of the upper at said toe portion. Thereupon a 15 hot iron is run over the fabric, the effect of which is to soften the rubber and the enamel coating, whereupon the adhesively coated fabric and the enamel coated upper are intimately united by the pressure and 20 heat. While the fabric and the upper are in a relatively warm or heated condition, the upper is lasted in the usual way. As is well known, the lasting operation consists of imposing an insole upon a last, drawing the 25 upper around the last and the insole so as to fasten the upper and insole together by the temporary lasting tacks, and then lasting the upper, such lasting operation being performed wholly by machinery, or partly by 30 hand and partly by machinery. In carrying out the invention as practised by me the lasting of the toe portion of the upper is effected by a lasting machine embodying wipers which engage with the inturned last- 35 ed toe portion of the upper so as to draw said toe portion tightly around the last. During the lasting of the upper with the fabric B in position thereon, the wipers of the lasting machine are in contact with the 40 fabric B, but said wipers do not come into contact with the enamel coated surface of the upper, so that the fabric protects the enameled upper from being cut or injured by the action of the wipers, and the wipers 45 cannot stick or adhere to the enamel coating during the lasting operation. The fabric covering thus remains in position upon the toe portion of the upper during the operation of pulling or straining the upper in 50 order to last it, and this fabric covering thus takes the strain off the enamel coating during the lasting operation. Subsequent to the lasting operation the fabric covering B remains attached to the shoe until the 55 manufacture of the shoe is completed and the last is removed. The fabric covering should now be removed, and this is accomplished in any suitable or desired way. The fabric is cut centrally down to the sole C and 60 the edges of the fabric are cut close to the sole or the upper so that no fragment of the fabric will be visible. When using rubber coated fabric as a protective medium for the enamel coated upper it is found that a thin layer of rubber will adhere to the enamel 65 coating subsequent to cutting off the fabric, but this rubber coating may easily be eliminated by the application of a suitable solvent, such as benzin, thereby cleaning the shoe. 70

From the prior description it is apparent that according to my mode of procedure the toe portion of the upper is lasted in such a way as to wholly preclude the enamel from cracking during such lasting operation and 75 subsequent to the lasting operation the fabric covering remains in position upon the lasted shoe so as to protect the enamel coating from contact with air for a sufficient length of time to allow the shoe to mold or shape itself 80 to the last and to enable the enamel to become set and hard, whereby the fabric covering acts to preclude cracking of the enamel during the period following the lasting operation. 85

Although I have described that the protective fabric is applied to the toe portion of the upper during lasting, it is apparent that the principle of my invention may be extended to other parts of the enamel coated 90 upper. Furthermore, any material suitable for the purposes of a protective covering may be employed. 95

My invention overcomes a most serious fault in the manufacture of enamel coated shoes and it enables a superior article to be produced with less labor and with material economy. 100

Having thus fully described the invention, what I claim as new, and desire to secure by Letters Patent is:

1. In the art of making enamel coated footwear the improvement which comprises protecting the enamel coating during the operation of lasting the upper in such manner that the coating is relieved from strain while lasting the upper. 105
2. In the art of making enamel coated footwear the improvement which comprises protecting the enamel coating during the operation of lasting the upper by applying and attaching a fabric to the enamel coated surface for taking off the strain due to lasting the upper. 110
3. In the art of making enamel coated footwear, the process which comprises attaching a fabric to the enamel coated surface of the upper, and subsequently lasting said upper with the fabric in contact therewith, said fabric operating to relieve the enamel coating from strain due to the lasting and, also, to preclude contact of air with said enamel coating subsequent to lasting. 115
4. In the art of making enamel coated footwear, the process which comprises attaching a layer of fabric in contact with the enamel coated surface of the upper, thereafter lasting the upper and said fabric 120
- 125

simultaneously whereby the attached fabric covers the enamel coated surface and is in contact therewith during said lasting operation, and finally detaching the fabric from the upper.

5. In the art of making enamel coated footwear the process which comprises applying and attaching a fabric to the coated surface of an upper prior to lasting, lasting 10 the upper with the fabric in contact with the enamel coating, and then after an appreciable interval of time within which the upper becomes set removing the fabric, whereby the enamel is precluded from cracking 15 by the strain imposed on the upper by lasting thereof and by contact of air with said enamel during the setting of the upper.
6. In the art of making enamel coated footwear the process which comprises positioning an adhesively coated fabric upon the 20 enamel coating of an upper, uniting said

fabric under heat and pressure to the coated surface of said upper, and lasting the upper with the fabric in position thereon.

7. In the art of making enamel coated 25 footwear the process which comprises positioning a rubber fabric upon the enamel coating of an upper, uniting said fabric under heat and pressure to said upper, lasting the upper and the fabric, retaining the 30 fabric in position upon the upper for an appreciable length of time subsequent to the lasting, and then removing the fabric from the upper.

In testimony whereof I have signed my 35 name to this specification in the presence of two subscribing witnesses.

JOHN A. KELLY.
